UNITED STATES PATENT OFFICE.

ELBERT WALKER SHIRK, OF PERU, INDIANA.

REFRIGERATOR.

1,084,366.

Specification of Letters Patent.

Patented Jan. 13, 1914.

Application filed March 7, 1913. Serial No. 752,534.

To all whom it may concern:

Be it known that I, ELBERT WALKER SHIRK, a citizen of the United States of America, and resident of Peru, Miami 5 county, Indiana, have invented a certain new and useful Improvement in Refrigerators, of which the following is a specification.

My invention relates to refrigerators of that kind in which separate ice and food 10 compartments are provided, the ice compartment being disposed above the food compartment, and in which a white enamel or other vitreous lining is employed for the interior thereof.

15 The principal object of my invention is to provide a refrigerator of the foregoing general character in which the said lining, although provided with a vitreous porcelain surface, is arranged to extend continuously 20 from the top to the bottom of the interior of the refrigerator, and from one chamber to the other, the bottom of the ice compartment being supported on shoulders or other projections formed on the said vitreous porcelain 25 surface, and the general construction of the refrigerator being such that the removable parts do not require an accurate fitting together thereof, especially so where contact is made between parts having the 30 said vitreous porcelain surface, whereby the use of the said vitreous porcelain lining is facilitated in the construction and manufacture of the refrigerator, and whereby the extension of the vitreous porcelain lining 35 from one chamber to the other, without any break in the continuity thereof, is rendered more possible and practical, both in the manufacture and the use of the refrigerator.

It is also an object to provide certain 40 details and features of improvement and combinations tending to increase the general efficiency and serviceability of a vitreous porcelain lined refrigerator of this particular character.

45 To the foregoing and other useful ends my invention consists in matters hereinafter set forth and claimed.

In the accompanying drawings: Figure 1 50 is a vertical section of a refrigerator embodying the principles of my invention. Fig. 2 is a perspective of the removable bottom of the ice compartment, and one of the removable flue walls, the two elements being shown assembled in their proper relative positions. Fig. 3 is a detail vertical section of the flue 55 walls shown in Fig. 2, showing adjacent

parts of the refrigerator body in section. Fig. 4 is a view similar to Fig. 3, showing the flue wall construction at the other side of the refrigerator. Fig. 5 is a plan of the 60 removable bottom of the ice compartment. Fig. 6 is an enlarged detail sectional view of the portion of the side wall of the refrigerator in which the trap is located for the drain. Fig. 7 is a detail vertical section of 65 one side of the ice compartment, and of a portion of the bottom of the ice compartment, showing the manner in which the flue wall is held in place by a flange on the side of the bottom. Fig. 8 is a perspective of the 70 lining of the ice compartment and food compartment, the said lining being of a unitary and continuous character, whereby it extends from one compartment to the other in the manner shown, without any break in the 75 continuity thereof—that is to say, without any break at the points where it passes the edges of the bottom of the ice compartment. Fig. 9 is a perspective view of the trap shown in Fig. 6, and of the receptacle there- 80 for.

As thus illustrated, the frame or body A of the refrigerator may be of any suitable, known or approved character. The ice compartment B is disposed above the food or 85 provision compartment C, as shown more clearly in Fig. 1, in the usual manner. Both compartments are provided with a lining in the form of a sheet metal box D, such as that shown in Fig. 8, the said lining extending continuously from one compartment to the other, and comprising vertical side walls d, a vertical back wall d¹, a bottom wall d², and vertical front flanges d³ which are connected by a cross-bar d⁴, which latter divides 95 the front of the lining into upper and lower openings, the upper opening being for the ice compartment, and the lower opening being for the food compartment. The said lining also has a top flange d⁵ at the front 100 thereof, and a lower upturned flange d⁶, which flanges are all perforated, as shown, for the purpose of securing the lining to the frame of the refrigerator. The four upper edges of the box-like lining D are provided 105 with horizontal flanges d⁷ for use in attaching the lining in place to the top of the refrigerator and body structure. The sheet metal cross-bar d⁴ is provided with a longitudinal crease or fold d⁸ that forms a supporting shoulder for the front edge of the bottom E of the ice chamber. The back wall 110

d^1 of the lining is provided with a similar fold or deflection in the metal, which provides not only a shoulder d^9 for the rear edge of the said bottom, but also a horizontal trough or gutter d^{10} which serves as a drain for the water that flows or drips from the rear edge of the said bottom. At one end of the said trough or gutter d^{10} a bent pipe F is inserted to carry off the water. The entire inner surface of the box-like lining D is covered with a vitreous porcelain coating, in any suitable manner, which forms an impervious inner surface for the two chambers. The said bottom E is composed of a flat core of wood e, a bottom layer of sheet metal e^1 , having a vitreous porcelain surface, and an upper layer of sheet metal e^2 that is also closed or covered with a vitreous porcelain surface. By referring to Figs. 2 and 7, it will be seen that the sheet metal facing e^2 is provided with upturned side edges forming flanges e^3 , which flanges serve to prevent the water from escaping at the sides of the bottom, and cause the entire quantity of water, produced by the melting of the ice, to drain off in the direction of the lower edge of the bottom, and into the trough or gutter d^{10} provided for this purpose. The front edge portion e^4 of the upper layer e^2 of the bottom extends forward and rests upon the upper edge of the cross-bar d^4 , and upon a suitable portion of the body frame, as shown more clearly in Fig. 1. The lower and rear edge of the bottom E is preferably provided with knobs or projections e^5 that bear against the back wall d^1 at points just above the trough or gutter d^{10} , thus insuring space between the lining of the refrigerator and the rear edge of the said bottom, which space is necessary for the proper discharge of the water from the bottom into the said trough or gutter. The flue walls G and H are arranged at opposite sides of the ice chamber, and have their lower edges disposed immediately inside of the flanges e^3 , in the manner shown more clearly in Fig. 7. Each flue wall is substantially pan-shaped in character, with the hollow side thereof turned outwardly, and the outer surfaces of these two walls are covered with a coating of vitreous porcelain, or with other equivalent enamel-like substance, similar to that used on the lining previously described. These flue walls are held in place by hooks g and h inserted in the sides of the ice chamber, said hooks being removably engaged by openings in the upper flanges of the flue walls, as shown more clearly in Figs. 3 and 4. The flue wall G is provided with openings g^1 near the lower edge thereof, for the circulation of the air, while the wall H is preferably plain or imperforate.

Referring to Figs. 6 and 9, it will be seen that the bent pipe F has its lower end in-

serted in one end of the trap f, which latter is in turn connected with the offtake pipe f^4 , whereby the water caused by the melting of the ice is carried off and discharged in any suitable manner. Preferably, however, this trap f is disposed between the side walls d of the lining and the outer wall a of the refrigerator frame or body, as shown more clearly in Fig. 6, sufficient space between the two walls being provided for this purpose. The said trap is inclosed in a sheet metal box f^1 which is set into the side wall of the refrigerator, with its open side facing outward, and which is provided with a cover f^2 of any suitable character. Thus, and by removing this cover f^2 , the said trap is rendered easily accessible for the purpose of cleaning or repair. The said box f is preferably secured in place by means of flanges f^3 formed around the edges thereof.

The refrigerator may be of any suitable, known or approved form of construction, so far as the number of compartments and the arrangement thereof are concerned, and the location and arrangement of the doors. For example, and as shown in Fig. 1, the refrigerator has a top I which has an inner lining or facing i of sheet metal covered with a porcelain surface, like that of the lining already described. This cover fits downwardly within the top of the ice chamber, but the porcelain surfaces do not fit or bear upon each other, as the flange i' of the cover rests upon the upper edges a¹ of the body of the refrigerator. The front of the refrigerator is provided with upper and lower doors J and K, which are similar in construction to the cover I, and which are allotted to the ice chamber and the food chamber respectively. The door J has an inner lining or facing j, which, like that of the cover I, is pan-shaped in character, with its hollow side facing outward, and is surfaced with vitreous porcelain or other equivalent enamel-like substance. The door K has a similar pan-shaped lining or facing k, and both of these doors are so constructed, it will be seen, that the vitreous porcelain surfaces do not have a tight fit or contact with the lining of the body, or with other portions of the refrigerator.

From the foregoing it will be seen that I provide a refrigerator in which the ice chamber is provided with a vitreous porcelain lining, and in which this lining extends continuously into the food or provision chamber, in the manner described, and without any break in the continuity thereto at the points where the lining extends downwardly past the bottom of the ice chamber. Thus the entire inner surface of the body of the refrigerator is impervious to moisture, and is entirely sanitary, being extremely easy to clean and keep in good condition. The construction, moreover, avoids the necessity of

any tight fit or contact between the vitreous porcelain surfaces, the movable and removable parts, to the contrary, being all assembled in a practically loose and non-fitting manner, whereby accuracy of fit, which is practically impossible with vitreous enamel surfaces, is not necessary, and is entirely avoided. The removable bottom of the ice chamber is loosely supported on shoulders which are formed integrally on the walls of the box-like sheet metal lining of the refrigerator, and which lining is surfaced or faced with vitreous porcelain extending continuously and in an unbroken manner from top to bottom of the refrigerator—that is to say, from top to bottom of the sides and back of the ice chamber and food chamber, in the manner described. The vitreous porcelain coating or surface can be applied to the sheet metal lining in any desired manner, and in any way known to those skilled in the manufacture of porcelain or enamel coated goods in general.

It will be understood, of course, that I do not limit myself to the exact construction shown and described, nor to the particular style of refrigerator shown and described. My invention, it will be understood, is applicable to the different types of refrigerators as well as the one shown and described. The continuous lining for the ice and provision chambers can be employed in a refrigerator in which the said chambers have any suitable and well known relative arrangement.

What I claim as my invention is:

1. A refrigerator having an ice chamber, a food chamber below said ice chamber, the ice chamber having a bottom for supporting the ice, and a continuous lining for said chambers, extending from one to the other, providing a vitreous inner surface therefor, said lining being formed with projections for removably supporting said bottom, a frame, and means for supporting the lining in said frame adjacent said projections.

2. A refrigerator having an ice chamber, a food chamber below said ice chamber, the ice chamber having a bottom for supporting the ice, and a continuous lining for said chambers, extending from one to the other, providing a vitreous inner surface therefor, said lining being formed with a gutter extending across one vertical surface thereof, disposed below one edge of said bottom to catch the drippings therefrom, and a drain opening in the lining at one end of said gutter.

3. A refrigerator having an ice chamber, a food chamber below said ice chamber, the ice chamber having a bottom for supporting the ice, and a continuous lining for said chambers, extending from one to the other, providing a vitreous inner surface therefor, said bottom being tilted down at its rear

edge, and said lining being formed with shoulders for supporting the front and rear edges of said bottom, the rear shoulder having a groove for carrying off the drippings from said bottom, the outer edge of said groove engaging said bottom, and means providing space between the rear edge of said bottom and the said lining.

4. A refrigerator having an ice chamber, a food chamber below said ice chamber, the ice chamber having a bottom for supporting the ice, and a continuous lining for said chambers, extending from one to the other, providing an impervious inner surface from top to bottom thereof, said lining being formed with projections for removably supporting said bottom, and means for backing and supporting said projections.

5. A refrigerator having an ice chamber, a food chamber below said ice chamber, the ice chamber having a bottom for supporting the ice, and a continuous lining for said chambers, extending from one to the other, providing an impervious inner surface from top to bottom thereof, said lining being formed with a gutter extending across one vertical surface thereof, disposed below one edge of said bottom to catch the drippings therefrom, the outer edge of said gutter forming a support for said bottom.

6. A refrigerator having an ice chamber, a food chamber below said ice chamber, the ice chamber having a bottom for supporting the ice, and a continuous lining for said chambers, extending from one to the other, providing an impervious inner surface from top to bottom thereof, and said lining being formed with shoulders for supporting the front and rear edges of said bottom, the rear shoulder having a groove for carrying off the drippings from said bottom, and means for backing and supporting said shoulders.

7. A refrigerator having an ice chamber, a food chamber below said ice chamber, the ice chamber having a bottom for supporting the ice, and a continuous lining for said chambers, extending from one to the other, providing a vitreous inner surface therefor, said lining being formed with projections for removably supporting said bottom, together with flue walls for the said ice chamber, provided with vitreous surfaces, and means for spacing said walls a distance from the sides of said ice chamber.

8. A refrigerator having an ice chamber, a food chamber below said ice chamber, the ice chamber having a bottom for supporting the ice, a continuous lining for said chambers, extending from one to the other, providing a vitreous inner surface therefor, said lining being formed with a gutter extending across one vertical surface thereof, disposed below one edge of said bottom to support the same and catch the drippings

therefrom, together with flue walls for the said ice chamber, and means for spacing said walls a distance from the sides of said ice chamber, above said bottom and gutter.

5 9. A refrigerator having an ice chamber, a food chamber below said ice chamber, the ice chamber having a bottom for supporting the ice, and a continuous lining for said chambers, extending from one to the other, 10 providing a vitreous inner surface therefor, said bottom being tilted down at its rear edge, and said lining being formed with shoulders for removably supporting the front and rear edges of said bottom, the rear 15 shoulder having a groove for carrying off the drippings from said bottom, together with flue walls for the said ice chamber, and means for spacing said walls a distance from the sides of said ice chamber, above 20 said bottom and gutter.

10. A refrigerator having an ice chamber, a food chamber below said ice chamber, the ice chamber having a bottom for supporting the ice, and a continuous lining for said 25 chambers, extending from one to the other, providing an impervious inner surface from top to bottom thereof, said lining being formed with projections for removably supporting said bottom, together with flue 30 walls for the sides of said ice chamber, means for removably suspending said walls a distance from the sides of the ice chamber, and means on said bottom for holding 35 said walls against outward displacement at the lower edges thereof, serving also to keep the water from dripping at the side edges of said bottom.

11. A refrigerator having an ice chamber, a food chamber below said ice chamber, the 40 ice chamber having a bottom for supporting the ice, a gutter disposed below one edge of said bottom, to catch the drippings therefrom, together with flue walls for the sides of said ice chamber, means for removably suspending 45 said walls a distance from the sides of the ice chamber, and means on said bottom for holding said walls against outward displacement at the lower edge thereof, serving also to keep the water from dripping 50 at the side edges of said bottom, and to direct the water into said gutter.

12. A refrigerator having an ice chamber, a food chamber below said ice chamber, the ice chamber having a bottom for supporting 55 the ice, shoulders for removably supporting the front and rear edges of said bottom, the rear shoulder having a groove for carrying off the drippings from said bottom, together with flue walls for the sides of said ice 60 chamber, means for removably suspending said walls a distance from the sides of the ice chamber, and means on said bottom for holding said walls against outward displacement at the lower edges thereof, serving 65 also to keep the water from dripping

at the side edges of said bottom, and to direct the water into said groove.

13. A refrigerator comprising an ice chamber, a bottom therefor, with space between the edges of said bottom and the surface of said chamber, at the sides thereof, flue walls for said chamber, each wall being pan-shaped with the hollow side thereof facing out, the upper flange of each wall being provided with holes, supports removably engaging said holes, fixed on the sides of said chamber, and flanges on said bottom, disposed outside the lower edges of said walls.

14. A refrigerator body frame having an 80 ice chamber, a food chamber below said ice chamber, the ice chamber having a bottom for supporting the ice, and a lining for said chambers, extending continuously throughout both chambers, providing a vitreous inner surface therefor, together with means for fastening the said lining at intervals to said frames.

15. A refrigerator body frame having an 90 ice chamber, a food chamber adjacent said ice chamber, the ice chamber having a bottom for supporting the ice, and a continuous lining for said chambers, extending from one to the other, providing a vitreous inner surface therefor, together with means 95 inserted through the lining at intervals to secure the same to said frame.

16. A refrigerator having an ice chamber, a food chamber adjacent said ice chamber, the ice chamber having a bottom for supporting the ice, and a continuous lining for 100 said chambers, extending from one to the other, providing a vitreous inner surface therefor, said lining being formed with a gutter extending across one vertical surface 105 thereof, disposed below one edge of said bottom to support the same and catch the drippings therefrom.

17. A refrigerator having an ice chamber, a food chamber adjacent said ice chamber, the ice chamber having a bottom for supporting the ice, and a continuous lining for 110 said chambers, extending from one to the other, providing a vitreous inner surface therefor, said bottom being tilted down at 115 its rear edge, and said lining being formed with front and rear shoulders for supporting the front and rear edges of said bottom, the rear shoulder having a groove below the supporting edge thereof for carrying off the drippings from said bottom.

18. A refrigerator having an ice chamber, a food chamber adjacent said ice chamber, the ice chamber having a bottom for supporting the ice, and a continuous lining 125 for said chambers, extending from one to the other, providing an impervious inner surface from top to bottom thereof, said lining being formed with projections for removably supporting said bottom, and 130

means for stiffening and supporting the lining adjacent said projections.

19. A refrigerator having an ice chamber, a food chamber adjacent said ice chamber, the ice chamber having a bottom for supporting the ice, and a continuous lining for said chambers, extending from one to the other, providing an impervious inner surface from top to bottom thereof, said lining being formed with a gutter extending across one vertical surface thereof, disposed below one edge of said bottom to catch the drippings therefrom, said bottom resting on the outer edge of the gutter, and means for spacing the edge of the bottom away from the lining above said gutter.

20. A refrigerator having an ice chamber,

a food chamber adjacent said ice chamber, the ice chamber having a bottom for supporting the ice, and a continuous lining for 20 said chambers, extending from one to the other, providing an impervious inner surface from top to bottom thereof, and said lining being formed with front and rear shoulders for supporting the front and rear 25 edges of said bottom, the rear shoulder having a groove for carrying off the drippings from said bottom, and a drain opening in the lining at one end of said groove.

Signed by me this 27th day of Feb., 1913. 30
